UNITED STATES PATENT OFFICE.

JOHN ROBERT CASPER, OF WASHINGTON, DISTRICT OF COLUMBIA.

SIGNALING DEVICE.

1,228,095.

Specification of Letters Patent. Patented May 29, 1917.

Application filed February 5, 1916. Serial No. 76,289.

To all whom it may concern:

Be it known that I, JOHN R. CASPER, a citizen of the United States, residing at Washington, District of Columbia, have invented certain new and useful Improvements in Signaling Devices, of which the following is a specification.

My invention relates to signaling devices for road vehicles and more particularly to 10 that type adapted for use upon automobiles to indicate the direction of travel thereof as when the operator proposes to round a corner, slow up or bring his vehicle to a full stop.

15 An object of the invention is to provide a simple, compact mechanism adapted to be secured to the rear of an automobile, preferably to the rear mud guard thereof, and which is easily discernible by pedestrians or 20 the occupants of other vehicles from either the front or rear of the automobile.

Other objects and advantages of the invention will be hereinafter set forth and the 25 novel features thereof defined by the appended claims.

In the accompanying drawings has been illustrated a simple and preferred form of the invention; it being however understood that no limitation is necessarily made to the 30 precise structural details therein, exhibited, but that changes, alterations and modifications within the scope of the invention, may be resorted to when desired.

35 In the drawings:

Figure 1 is a front elevation invention, the signal plate being elevated and the red light showing.

Fig. 2 is a sectional elevation, the operative parts being shown in their normal position with the signal plate removed.

Fig. 3 is a top view with the cover of the casing removed, the parts being in the position shown in Fig. 2.

Fig. 4 is a sectional elevation of the operative parts removed from the casing, the semaphores being down in full lines and up in dotted lines.

Fig. 5 is a detail view of the metal disk and contiguous parts of the casting.

50 Referring more particularly to the drawings in which like numerals of reference refer to corresponding parts in the several figures 1 is a casing adapted to be securely fastened to the rear mud guard of an automobile (not shown) by any suitable means such as bolts 2, a suitable closure member 3

being provided to protect the interior of the casing from the elements.

Inclosed within the casing and secured to the inner side wall thereof by means of bolts 60 4 is a casting or support 5 designed to compactly contain and securely support the signaling mechanism. The casting comprises an upright opensided rectangular frame 6 extending from one side of which is a web 65 or flange 7 formed with slotted cross-arms 29 through which the bolts 4 extend. Formed on the opposite side of the casting are similar upper and lower open-sided angularly disposed, rectangular frames 8 and 70 9 respectively for a purpose hereinafter described. A pair of upstanding ears 10 and a vertically disposed arm 11 complete the casting.

The ears 10 are provided with apertures 10' 75 forming bearings for a transverse shaft 12 detachably mounted upon the extended ends of which are a pair of arms 13 and 14. These arms are formed with sleeves 15 and 16 which receive the respective ends of the 80 shaft, set screws 17 and 18, extending through the sleeve serving as means for rigidly attaching the arms to the shaft. Each arm is formed with a counter weight 85 adjacent its pivoted end as at 19 and 20, and the opposite ends respectively carry a circular glass 21 and 22 of reddish tinge forming semaphores 23 and 24 such arms normally lying in a vertical position with respect to the casing, the circular glasses 21 90 and 22 of the arms 13 and 14 alining with glazed openings 25 and 26 of greenish tinge formed in the adjacent walls of the casing.

Mounted in the upper end of the arm 11 is a shaft 27 formed adjacent one end thereof with a counter weight 28 and carrying at the other end a sleeve 30 adapted to fixedly receive the shaft. The sleeve 30 is formed with an apertured lug 31 and a reduced extension 32, adapted to project through an opening 33 in the casing. Formed on the extremity of this extension is an arm 34 having a finger 35 projecting at right angles therfrom to which is suitably secured a signal plate 36 or the like of reddish tinge and bearing the word "Caution." This plate when in inoperative position is hidden from view by a covering plate 52 attached to the front wall of the casing.

A link 37 is connected at its opposite ends 110 to the apertured lug 31 on sleeve 30 and to a similar apertured lug 38 formed on the

sleeve 15 of arm 13, screws or other suitable fasteners 39 and 40 being employed for this purpose. It will thus be seen that any rotary movement imparted to the shaft 12 5 will be communicated to the shaft 27 and consequently to the caution signal plate 36 and semaphores 23 and 24.

Each of the frames 6, 8 and 9 contains a solenoid coil 41, 42 and 43 respectively connected by suitable wiring of any well known type, not shown, to a point convenient to the operator so that he may at pleasure energize the magnets and cause the signal to be operated in the following manner.

Assuming the parts to be in the position shown in Fig. 2 of the drawings and the operator desires to show the caution signal he will momentarily energize the magnet 41 causing the iron core 44 thereof to be retracted. This reciprocal movement of the plunger imparts a corresponding rotary movement to the shaft 12 by virtue of the curved arm 45 connecting the shaft and plunger together, as best illustrated in Fig. 4. The caution signal 36 and consequently the semaphores are thus elevated to horizontal position (see Fig. 1) where they are automatically locked by the spring pressed core 46 of solenoid 43 entering a slot 47 formed in a metal disk 48 in turn fixed to the shaft 12. At night an electric light 49 suitably mounted between the two semaphores may be switched on thus showing a red light through the openings 25 and 26 in the casing. When the semaphores are in vertical position and out of alignment with the openings it will of course be understood that a green light will show both to the front and rear of the machine.

Should the operator now energize the solenoid 43 causing the soft metal core 46 thereof to be retracted from the slot 47, the caution plate and semaphores will be returned to vertical or inoperative position by force of gravity and locked in such position by the spring pressed metal core 51 of solenoid 42 engaging in a second slot 52 formed in the periphery of the disk 48. It will of course be understood that solenoids 41 and 42 are connected in series so that the spring pressed core of the latter will be disengaged from locking position when the former is energized for the purpose of showing the danger signal.

In order to prevent the spring pressed locking cores 46 and 51 from sticking to the disk 48, due to any residual magnetism, and thus rendering the respective solenoids inoperative the cores are provided with tips 46' and 51' of brass or other nonconducting material which engage the slots.

From the foregoing it will be seen that I have provided an apparatus which is compact, economical to operate and comparatively cheap to construct.

Having thus described my invention, what I claim is:

1. A signaling device for automobiles comprising a casing having glazed openings therein, a support within said casing, a shaft 70 rotatably mounted in said support, a pair of semaphores fixed to said shaft and adapted in inoperative position to be out of alignment with said glazed openings, a second shaft mounted on said support and having one end projecting through a wall of the casing, a caution signal secured to said projecting end, a counter weight on the other end of said shaft, said caution signal being adapted to be hidden from view when said semaphores are in inoperative position and means connecting said shaft whereby when said semaphores are moved to operative position said caution signal will be exposed to view.

2. A signaling device for automobiles comprising a casing, a support within said casing, a pair of parallel shafts mounted in said support, means for rotatably connecting said shafts together, a caution signal plate connected to one of said shafts outside the casing wall, a sleeve mounted on the other of said shafts, a slotted disk formed on said sleeve, a solenoid magnet, a curved arm connecting the core of said magnet with said sleeve whereby when said magnet is energized the shaft may be rotated, a pair of solenoid magnets having spring pressed cores adapted to engage the slots in said disk to lock said signal plate in operative or inoperative position.

In testimony whereof I affix my signature in presence of two witnesses.

JOHN ROBERT CASPER.
